UNITED STATES PATENT OFFICE.

WILLIAM W. SLOANE, OF CHICAGO, ILLINOIS, ASSIGNOR TO GOODMAN MANUFACTURING COMPANY, OF CHICAGO, ILLINOIS, A CORPORATION OF ILLINOIS.

MINE-LOCOMOTIVE.

1,358,028.

Specification of Letters Patent.

Patented Nov. 9, 1920.

Application filed May 4, 1920. Serial No. 378,874.

To all whom it may concern:

Be it known that I, WILLIAM W. SLOANE, a citizen of the United States, residing at Chicago, in the county of Cook and State of Illinois, have invented an Improvement in Mine-Locomotives, of which the following is a specification.

This invention relates to improvements in mine locomotives and has for its principal object to provide a single-motor locomotive having a pair of flexibly mounted driving axles in which the overall height of the locomotive can be reduced to a minimum, so as to be particularly adaptable for use in mines. 10
15 In my pending application for Letters Patent, Serial #351,600, filed January 15, 1920, I have described a construction of storage battery locomotive in which two axles are pivotally mounted on the main frame of the locomotive and the power is transmitted to the axles from a single-motor also mounted on the frame, through a pair of intermediate gears in vertical alinement with the pivots. The storage battery is mounted on springs over the motor and main frame. 20
25
30

The present invention differs from the prior construction above described, in that the main frame, which includes the entire locomotive with the exception of the motor and running gear, is mounted on springs of the usual type, and journaled on the outside ends of the axles, while the motor is suspended between, and connected to the axles by substantially the same method of pivoted construction above described, but independent of the main frame. It will be seen that the improved construction affords a full spring suspension for the main frame of the locomotive, thereby imparting easier riding qualities thereto, but retaining the advantageous features of a single-motor drive having a relatively large wheelbase and minimum height, disclosed in the prior application. Furthermore, when storage batteries are employed, it allows the batteries to be carried on the two ends of the main frame, thereby providing a greatly reduced overall height for such a storage battery locomotive and eliminating the necessity of a separate spring suspension for the battery box. 35

50

The invention consists in the combination, construction, and arrangement of parts as

will hereinafter be described in connection with the accompanying drawings, and more particularly defined in the appended claims.

In the drawings Figure 1 is a view in elevation of a locomotive embodying my invention.

Fig. 2 is a top plan view of the locomotive.

Fig. 3 is an enlarged vertical cross section taken on line 3—3 of Fig. 2.

Fig. 4 is an enlarged cross-section taken on line 4—4 of Fig. 2.

Fig. 5 is a vertical cross-section taken on line 5—5 of Fig. 2, illustrating details and arrangement of the driving mechanism.

In the embodiment of my invention illustrated, a locomotive 1 is provided with a main frame 2, a pair of axles 3, 3 with supporting wheels 3^a, 3^a, and journal boxes 4, 4, on the outer ends of the axles, and supporting the frame 2 by suitable spring suspension devices such as helical springs 5, 5. 70
75

In addition to the supporting means for the main frame above described, the axles 3, 3 also carry the motor casing or support 6 suspended therebetween by means of a pair of brackets 7, 7, each journaled on an axle 3 by bearings 8, 8, and pivoted near one end thereof on horizontally disposed pins 9, 9, mounted on arms 10, 10 carried by the motor casing or support 6. The pivot pins 9, 9 are preferably located in alinement with each other beyond one end of the motor casing 6, and above the axles, as shown in Fig. 3. The opposite unpivoted end of the casing 6 is flexibly supported on the axles in any suitable manner, preferably by means of a pair of vertically disposed springs seated in stirrups 11, 11, extending from the sides of the motor casing 6 and seated on the brackets 7, 7, as shown. It will be seen that this pivoted construction allows one axle to swing in relation to the other axle so the wheels may remain in contact with the rails during the operation of the locomotive over uneven track. In the preferred construction shown, both axles 3, 3, are pivoted to the motor housing, but it is manifest that substantially the same flexibility of the truck will result if only one of the axles is mounted on a pivoted bracket, and the other mounted rigidly with respect to the motor casing. 80
85
90
95
100
105

Suitable spacing sleeves 8^a, 8^a, are inserted on the axles 3, 3, between the wheels 110

3^a, 3^a, and bracket journals 8, 8. The width of these spacing sleeves may be changed to accommodate variations in track widths, as desired.

5 The locomotive is driven by a single electric motor 12, in the casing 6, before mentioned, and provided with an armature 13, an armature shaft 14, and bearings 15, 15 for said shaft. A brake drum 16, is preferably mounted on the armature shaft near one end, as shown.

10 The motor armature 13, is interposed between the axles 3, 3, and parallel therewith so that the greatest width of the motor, represented by the pole-pieces 17, 17 is located between, and extending below the axles, as shown. This arrangement allows the motor to be set as low between the axles as is practicable, as it will be seen that the bottom wall of the motor casing 6 establishes the clearance of the locomotive over the center of the roadbed. The motor 12 may be of any approved type. Means of access to the motor comprises a removable 15 cover plate 18 on the casing 6, preferably arranged to carry one of the pole-pieces 17, and split on an angular plane so as to be easily removed from the armature.

20 The power transmission comprises the armature shaft 14, pinion 19 on said armature shaft, two intermediate gears 20, 20, mounted on pins 21, 21 carried by the motor casing on opposite sides of said armature pinion, and gear wheels 22, 22, preferably mounted on the axles 3, 3. The arrangement is such that the intermediate gears 20, 20, rotate in substantially the same vertical plane as the axis of the pivots 9, 9. This arrangement of gearing allows each axle to 25 swing on its respective pivot, while maintaining driving connection between the axle gear 22, and its respective intermediate gear 20, in all permissible positions of the axle. It will be observed that the main feature 30 of the driving mechanism just described, is the provision of a meshed relation between an intermediate gear 20, and a suitable gear carried by a bracket 7, at a point substantially in the same vertical plane as the axis 35 of a pivot 9. In other words, the power transmission mechanism carried on the pivoted brackets has a continuous driving connection with the mechanism mounted on the motor casing in the manner shown. I do 40 not, however, wish to be understood as limiting myself to the particular form of driving mechanism which I have shown herein, excepting as specifically limited in the appended claims.

45 From the foregoing description, it will be clear that I have provided a locomotive of the single-motor, flexibly mounted axle type, in which a full spring suspension is provided for the main frame of the locomotive. With such a construction, the wheel 50

base may be made of sufficient length to allow storage batteries of considerable bulk and weight to be carried in suitable compartments 23, 24, on the ends of the main frame, without causing an excessive amount 70 of "teetering" motion, which is objectionable in locomotives of this type. This construction therefore, provides a means of reducing the overall height of the locomotive, including the storage batteries, to a minimum. 75

Having described my invention what I claim as new and desire to cover by Letters Patent, is:

1. A locomotive having a main frame, two 80 axles laterally spaced apart, a motor, a support for said motor independent of said main frame, said support including a horizontally disposed pivot affording movement of one of said axles out of parallelism with 85 the other axle, and a gear carried by said support and affording an operative connection with said pivoted axle at a point substantially in line with said pivot.

2. A locomotive having a main frame, two 90 axles laterally spaced apart, a motor having its greatest width between and extending below said axles, a support for said motor journaled on said axles and affording movement of said axles in a vertical plane independent of each other, spring suspension means for said main frame independent of said motor support, and two gears mounted on said motor support, each arranged intermediate said motor and one of said axles, 95 and forming an operative connection therebetween.

3. A locomotive having a main frame, two axles laterally spaced apart, a motor having its greatest width between and extending below said axles, a support for said motor independent of said main frame, said support including a horizontally disposed pivot affording movement of one of said axles out of parallelism with the other axle, 105 and a driving connection between said motor and said pivoted axle.

4. In a locomotive, the combination of a main frame, two axles laterally spaced apart, a motor having its greatest width between and extending below said axles, a support for said motor, spring suspension means for said main frame independent of said motor support, a gear carried by said support intermediate said motor and one of 115 said axles, forming an operative connection therewith, and means connecting the last named axle to said support and affording movement of said axle substantially in a vertical plane whereby said gear is maintained 120 in driving connection with said axle in all its various positions.

5. A locomotive having a main frame, two axles laterally spaced apart, a motor having its greatest width between and extending 130

below said axles, a support for said motor independent of said main frame, said support including a horizontally disposed pivot affording movement of one of said axles out of parallelism with the other axle, and a gear carried by said support and affording an operative connection with said pivoted axle at a point substantially in line with said pivot.

10 6. A locomotive having a main frame, two axles laterally spaced apart, a motor having its greatest width between and extending below said axles, a support for said motor independent of said main frame, said support including a horizontally disposed pivot affording movement of one of said axles out of parallelism with the other axle, and a train of gears mounted on said motor support, having an operative connection with 15 said pivoted axle at a point substantially in line with said pivot.

7. A locomotive having a main frame, two axles laterally spaced apart, a motor, a sup-

port for said motor including a horizontally disposed pivot near one end thereof affording movement of one of said axles out of parallelism with the other axle; means flexibly supporting the unpivoted ends of said motor support on said pivoted axle, an operative connection between said motor and said pivoted axle, and spring suspension means for said main frame on said axles.

8. A locomotive having a main frame, two axles laterally spaced apart, a motor, a support for said motor including horizontally 35 disposed pivots near one end thereof affording movement of said axles out of parallelism with each other; means flexibly supporting the unpivoted end of said motor support on said pivoted axles, an operative connection between said motor and said pivoted axles, and spring suspension means for said main frame on said axles.

Signed at Chicago, Illinois, this 30th day of April, A. D. 1920.

WILLIAM W. SLOANE.
